UNITED STATES PATENT OFFICE.

JAMES HARRY KEIGHLY McCOLLUM, OF TORONTO, CANADA, ASSIGNOR OF
TWO-THIRDS TO REMIGIUS ELMSLEY AND WILLIAM HENRY BROUSE,
OF SAME PLACE.

CAR-BRAKE.

SPECIFICATION forming part of Letters Patent No. 645,486, dated March 13, 1900.

Application filed February 11, 1899. Serial No. 705,311. (No model.)

To all whom it may concern:

Be it known that I, JAMES HARRY KEIGHLY McCOLLUM, electrician, of the city of Toronto, in the county of York, in the Province of Ontario, Canada, have invented certain new and useful Improvements in Car-Brakes, of which the following is a specification.

My invention relates to improvements in car-brakes; and the object of the invention is to design a simple, cheap, and effectual brake capable of being applied in various ways with but a minimum exertion of power and loss of time; and it consists, essentially, of a sheaf secured to the axle and provided with an encompassing strap or band, which is connected by cable or chain to the brake-levers, against which strap a shoe, pivoted to the internal sheaf, is designed to be frictionally brought, such shoe being pivotally supported on a lever and tilted on its pivot by means of a rocking arm the bottom end of which extends into a recess in a collar, which is supported loosely on a collar on the shaft, the former collar being engaged by brake-shoes pivotally connected to suitable hangers, which are operated to throw in the coacting minor brake-shoes in the manner hereinafter more particularly explained.

Figure 1 is a skeleton perspective view showing my brake mechanism. Fig. 2 is a cross-section through the wheel and band. Fig. 3 is a perspective detail showing the mode of connection of the band to the cable of the brake-levers. Fig. 4 is a detail of the lever and internal brake-shoe. Fig. 5 is a detail of an alternative form of rocking arm and gear. Fig. 6 is a side elevation showing the manner of operating my brake when applied to a railway-car. Fig. 7 is a side elevation showing the construction adopted when applied to a trailer-car.

In the drawings like letters of reference indicate corresponding parts in each figure.

A is one of the axles of the car, and B the wheels.

C is a sheaf suitably secured on the axle, and C' is a collar attached to or forming part of the sheaf C. The sheaf C is preferably formed in two parts suitably bolted together and to the axle.

D is a strap or band which surrounds the

sheaf C and has secured to it the annular face guiding-rims D'.

E is a brake-lever which is suitably pivoted to a brace F, secured to the bottom of the car, which bottom is not shown.

G are the brake-shoes, which are connected together by the usual cross-bar G'. The cross-bar G' is connected by a rod G² to the brake-lever E.

H is a cable formed of wire rope, chain, or other suitable material, connected at one end to the brake-lever E on the opposite side of the pivot-point to that to which the rod G² is connected. The opposite end of the cable H passes through a guiding-bracket H' and is connected to an eye d, which straddles the joint of the strap D and extends over same.

I is a supplemental collar loosely supported on the collar C', and J is a rocking arm provided with an upper double end suitably pivoted on the sheaf C and having the lower end extending into a recess i in the collar I.

K is an arc-shaped lever pivoted on the pin k on the sheaf C and provided with the shoe K', pivoted at k' on the lever. The arc-shaped lever extends partially around the face of the wheel and over the rocking arm, as indicated.

L, L' are two supplemental brake-shoes which have lugs l l' formed on them respectively, by which they are pivotally connected to the lower forks of the hangers M M'. The supplemental brake-shoes are located one at each side of the axle, and the brake-shoe L is provided with an oil-cup l', which extends over the axle. The hangers M and M' are pivotally connected at the bottom to the cross-bar.

The hanger M is pivoted at the top on the pin m², which extends through the double bars N and N, suitably supported on the bottom frame of the car. The upper end of the hanger M' is connected by the double rod O O and single rod O' to the frame, the single rod extending through a plate o on the end of the double rod and having on its end a disk o', between which and the plate o extends the spiral spring o². The hanger M' is also connected by the pivoted bracket P and the rod Q, extending through the end thereof, to the lever R, pivoted at r on a suitable portion of the frame.

The lever R is connected by the rod S to

the lever T, pivoted on a suitable portion of the frame at t, and the lever T is connected by the link U to the operating-lever V, as indicated.

- 5 The normal tendency of the spring o² is to throw the hangers apart, and consequently relieve the pressure of the shoes L and L' upon the collar I.

In order to put on the brake, the operating-lever V, controlled by the motorman of the car, is pulled backward, thereby through the system of levers hereinbefore described drawing upon the hanger M', thus forcing the shoes L and L' against the collar I. The rotation of the collar is thereby retarded; but the wheel C, continuing to move around, the rocking arm connected to it is tilted on its pivot, thereby throwing the arc-shaped lever and brake-shoe into engagement with the interior of the strap D, thus causing the band to move around with the wheel and pulling upon the cable, and consequently upon the brake-lever and brake-shoes. It of course will be understood that in the stopping of the car the shoes L and L' will necessarily slip to some extent as long as the brake is being applied and until the car is brought to a standstill.

In Fig. 5 I show a somewhat different form of rocking arm J', which has a quadrant at the lower end meshing with a gear-wheel I', attached to the collar I. Inside the strap or band D and outside the wheel are two arc-shaped segments K² K², which are pivotally connected at k² k² to the sheaf and are separated at the top by the top of the rocking arm. When the rocking arm is tilted on its pivot by means of the collar I being retarded by the shoes, it will be seen that the quadrant of the rocking arm J will be tilted the same as before, and the upper end will necessarily spread apart the ends of the segmental pieces K², thereby putting on the brake. In both of these cases described immediately the operating-lever is released the spiral extension-spring o² will draw the hanger M', and consequently the brake-shoes L L', away from the collar and relieve the brake mechanism.

In Fig. 6 I show a means for operating my brake mechanism hereinbefore described more particularly adapted for railway-trains. W is a solenoid, which is one of a series throughout the several cars, and w is the reciprocating core and w' the wires leading throughout the length of the train to the several solenoids. Ordinarily the hanger M', which in this case is really an armature, is held away, so as to keep the shoes L and L' from contacting with the collar I, by means of the solenoid. By means of a small dynamo used in the engine the current is supplied to the solenoids throughout the length of the train, and by shifting the brushes thereon or the use of resistance in series the current is taken from the solenoid and the rod o³ is forced by the spring o⁴, so as to shift the hangers M', and thereby spring the shoes into

engagement with the collar and operate the brake mechanism hereinbefore described. Instead of using the solenoid for keeping the hanger M' and the spring for drawing the hanger close to apply the shoes they might be used vice versa.

In Fig. 7 I show my device designed to be operated in a trailer through the draw-bar. 75 X is the draw-bar, and x is a lever pivotally connected thereto and to the lever S, identically constructed to that shown in Fig. 1. Y is a face ratchet-wheel formed on one of the rims of the strap or the band. The ratchet-wheel Y is engaged by a pawl y, connected by a rod y', extending between the cars and to the front motor-car, where it is connected to a crank Y', operated by a push-rod Y², which may be pressed downwardly to withdraw the dog when it is desired to release the brake on the trailer. The operation of the brake in other respects, however, is the same as when put on by the operating-rod described in Fig. 1. The draw-bar X of course 90 takes the place of this operating-rod and acts in a similar manner thereto.

The double bars, which I have hereinbefore described, it will be seen act as a guide for retaining the hangers M and M' on a line with each other and with the loose collar, so that 95 there is no danger of binding.

What I claim as my invention is—

1. The combination with a brake-shoe, 100 brake-lever and connecting-rods, of a sheaf secured to the axle, a strap completely encircling the sheaf and permanently of greater diameter than the sheaf and expanding means adapted to be moved outwardly to engage the strap frictionally, and a cable connecting 105 the strap to the brake-lever, substantially as described.

2. The combination with the brake-shoes, 110 brake-lever and connecting-rods, of the sheaf secured to the axle, the strap loosely mounted on same, the cable connecting the strap to the brake-lever, the loose collar I, means for frictionally engaging the sheaf with the strap and means for retarding the rotation of the loose collar as and for the purpose specified. 115

3. The combination with the brake-shoes, 120 brake-lever and connecting-rods, of the sheaf secured to the axle, the strap loosely mounted on same, the cable connecting the strap to the brake-lever, the collar attached to or forming part of the sheaf, the loose collar mounted on same and provided with a recess, the rocking bar extending into such recess and means on the sheaf operated by the rocking bar for frictionally connecting the sheaf to the strap 125 as and for the purpose specified.

4. The combination with the brake-shoes, 130 brake-lever and connecting-rods, of the sheaf secured to the axle and the strap loosely mounted on same and the cable connecting the strap to the brake-lever, the collar attached to or forming part of the sheaf, the loose collar mounted on same and provided with a recess, the rocking bar extending into

such recess and the arc-shaped lever pivoted to the sheaf extending over the rocking arm and provided with a frictional contacting braking-surface designed to come in contact 5 with the strap and means for retarding the rotation of the loose collar as and for the purpose specified.

5. The combination with the brake-shoes, brake-lever and connecting-rod, the axle, the 10 sheaf secured thereto, the strap mounted on said sheaf, the brake-lever, the cable connection between the same and the strap, the collar moving with the sheaf, the loose collar mounted thereon, the rocking bar, the pivoted 15 lever, a brake-shoe carried thereby adapted to engage said strap and a connection between the lever and the loose collar for actuating said brake-lever to apply said brake-shoe, substantially as described.

20. 6. The combination with the brake-shoes, brake-lever and connecting-rod, of the sheaf secured to the axle, and strap loosely mounted on same and the cable connecting the strap to the brake-lever, the collar attached to or 25 forming part of the sheaf, the loose collar mounted on same, the arc-shaped lever pivoted on the sheaf, provided with a frictional contacting-surface, and designed to engage with the strap, means connected to the loose 30 collar for tilting the arc-shaped lever and means for retarding the rotation of the collar as and for the purpose specified.

7. The combination with the brake-shoes, 35 brake-lever and connecting-rod, of the sheaf secured to the axle, and strap loosely mounted on same and the cable connecting the strap to the brake-lever, the collar attached to or forming part of the sheaf, the loose collar mounted on same, the arc-shaped lever pivoted on the sheaf, provided with a frictional 40 contacting-surface, and designed to engage with the strap, means connected to the loose collar for tilting the arc-shaped lever, the shoes suitably supported in proximity to the 45 loose collar and means for throwing them against the said collar as and for the purpose specified.

8. The combination with the brake-shoes, 50 brake-lever and connecting-rod, of the sheaf secured to the axle, and the strap loosely mounted on same and the cable connecting the strap to the brake-lever, the collar attached to or forming part of the sheaf, the loose collar mounted on same, the arc-shaped 55 lever pivoted on the sheaf, provided with a frictional contacting-surface, and designed to engage with the strap, means connected to the loose collar for tilting the arc-shaped lever, the minor shoes, the hangers both pivotally connected to the shoes and one pivotally supported at the top, the bottom bar con-

necting both hangers at the bottom and means for drawing the hangers together to apply the shoes as and for the purpose specified.

9. The combination with the brake-shoes, 65 brake-lever and connecting-rod, of the sheaf secured to the axle and strap loosely mounted on same and the cable connecting the strap to the brake-lever, the collar attached to or forming part of the sheaf, the loose collar 70 mounted on same, the arc-shaped lever pivoted on the sheaf, provided with a frictional contacting-surface, and designed to engage with the strap, means connected to the loose collar for tilting the arc-shaped lever, the 75 shoes, the hangers both pivotally connected to the shoes and one pivotally supported at the top, the bottom bar connecting both hangers at the bottom, means for drawing the hangers together to apply the shoes and a suitable 80 spring-actuated device for separating the hangers to release the shoes as and for the purpose specified.

10. The combination with the brake-shoes, 85 brake-lever and connecting-rod, of the sheaf secured to the axle, and strap loosely mounted on same and the cable connecting the strap to the brake-lever, the collar attached to or forming part of the sheaf, the loose collar mounted on same, the arc-shaped lever pivoted on the sheaf and provided with a frictional 90 contacting-surface and designed to engage with the strap, means connected to the loose collar for tilting the arc-shaped lever, means for retarding the rotation of the collar, 95 the ratchet-wheel formed on the face of the strap, the pawl engaging therewith and means for releasing such pawl as and for the purpose specified.

11. The combination with the brake-shoes, 100 brake-lever and connecting-rod, of the sheaf secured to the axle, and the strap loosely mounted on same and the cable connecting the strap to the brake-lever, the collar attached to or forming part of the sheaf, the 105 loose collar mounted on same, the arc-shaped lever pivoted on the sheaf provided with a frictional contact-surface, and designed to engage with the strap, means connected to the loose collar for tilting the arc-shaped 110 lever, the minor shoes, the hangers, the double bar forming a support for the pivoted hanger and a guide for the loose hanger, means for connecting the hangers at the bottom and means for drawing such hangers together to apply the brake as and for the purpose specified.
